VERTICALLY ADJUSTABLE TABLE FOR
OFFICE APPLIANCES

Wright K. Gannett and Gifford M. Mast, Davenport, Iowa, assignors to Le Febure Corporation, Cedar Rapids, Iowa, a corporation of Iowa

Application July 24, 1948, Serial No. 40,466

6 Claims. (Cl. 311—39)

1

This invention relates to elevating office stands and has particular relation to an adjustable table structure suitable for supporting loose leaf ledgers, file boxes and like articles, at whatever height is most convenient for the user.

While numerous devices have been proposed for making table tops adjustable with relation to the floor, such devices have usually employed screw jacks, hydraulic jacks, or other similar mechanisms, and raising or lowering of the table required manipulation of these raising or lowering mechanisms. Others have been unreliable as well as relatively complicated and expensive to build.

A primary object of our invention is the provision of a dependable, elevating stand or adjustable table of simple construction and one having adequate capacity to handle any ordinary load likely to be placed upon it, but so arranged as to operate easily with but relatively little force applied directly to the table top.

It is imperative, in tables of the character considered, that the surface of the table top will always be level, regardless of its distance above the floor, and therefore another main object of our invention is to provide a table in which the top surface is maintained parallel to the plane of the floor, regardless of the height to which it is adjusted.

Still another object of our invention is to provide simple means for compensating for variation in the weight of the load being carried on the table or supported thereby.

Other and further features and objects of the invention will be more apparent to those skilled in the art upon a consideration of the accompanying drawings and following specification, wherein is disclosed a single exemplary embodiment of the invention, with the understanding, however, that such changes may be made therein as fall within the scope of the appended claims, without departing from the spirit of the invention.

In said drawings:

Figure 1 is a view in perspective of an elevating table constructed according to a preferred embodiment of my invention.

Figure 2 is a view in perspective of the table in collapsed or lowered position. The table is viewed from the end opposite that illustrated in Figure 1.

Figure 3 is a view, partly in side elevation and partly in longitudinal vertical section, of my elevating table, and

Figure 4 is a fragmentary view in end elevation of the device illustrating some of the details of the elevating mechanism.

2

Referring now to these drawings, and in particular to Figures 1 and 2 thereof, in which a table top 11 is supported above a base member, indicated generally at 12, by means of a plurality of arms pivotally connected therebetween, the arms being so positioned as to form the sides of spaced parallelograms as shown at 13. Counterbalancing of the weight of the table top 11 and any load placed upon it is accomplished by means of coiled tension springs 14 operatively connected with the arms, as will be hereinafter more fully described, and by means of a tension adjustment indicated in general at 16. The table top, when adjusted to suit the convenience of the user, is secured against further up-or-down movement by means of the locking mechanism 17.

The base member 12 is of rectangular shape and preferably constructed of sheet metal in generally box-like form, as at 18, and supported at 20 the corners by the casters 19.

A pair of plate-like base flanges 21 and 22 are secured, along their lower edges, to the side walls of the base 12 adjacent one end thereof. These flanges may be of generally triangular shape and 25 are apertured at vertically and horizontally spaced points to receive the pivot bolts 23 and 24. The table top 11 may also be of sheet metal construction having down-turned, flanged edges, as at 26, for rigidity. Additional reinforcing members 27—27, secured to the longitudinal edges of the top, extend thereabove to provide a partial rim. Depending from these longitudinal edges of the table top are a pair of top flanges 28 and 29. These members are preferably of 30 similar shape to the base flanges 21 and 22, and in the same planes, and so positioned that the near edges 28a and 21a of each pair are substantially parallel.

The top flanges 28 and 29 are apertured in a 35 manner similar to the base flanges to receive pivot bolts 31 and 32 and at points such that the apertures and the bolts of the companion flanges on each side of the table form the parallelograms 13.

The sides of each parallelogram are formed by a pair of spaced, upper and lower pivot arms, 33 and 34 respectively, these members being of equal length between apertures provided adjacent each end thereof for reception of the pivot bolts 24—32 and 23—31. The pivot arms, which may be formed of metal, may have their upper edges bent over, as at 33a and 34a, for reinforcement. The pivot bolts are mounted through their respective holes in the flanges members and pivot arms and secured by nuts 36, washer-like spacers 37 being positioned between each flange and arm.

A tube-like spacer 38 is welded between the upper pivot arms 33 at their points of pivotal connection with the lower flanges, the ends of the spacer being plugged and tapped to receive the pivot bolts 24.

The lower pivot arms 34 are extended at their lower ends to provide lever arms 39 between the ends of which a channel-shaped cross member 41 is attached by bolting or spot welding, as at 42.

The tension adjusting mechanism includes, in addition to the cross member 41, an equalizer bar 43 of generally box-like form which is pivotally mounted between the lowermost ends of the lever arms 39 upon studs 44 which extend through openings in the end walls 43a of the cross member.

Ear-like members 46 project outwardly from the movable wall 47, of this equalizer bar 43, adjacent each end thereof and are apertured, as at 48, to permit engagement with the hooked ends of the springs 14-14. The opposite ends of the springs are engaged to anchor plates 49, which members are secured to the base at points sufficiently remote from the cross member 43 to create an initial tension in the springs. This initial tension should be such that, when the equalizer bar 43 is adjusted to the position illustrated at 43b by dotted lines, and at which position the effective lengths of the lever arms 39 are the shortest, the weight of the table top and attached movable mechanisms will be substantially counterbalanced.

In order to move the equalizer bar 43 downwardly and thus increase the effective length of the lever arms 39, we provide the threaded adjusting screw 51. This screw is provided, near its upper end, with a collar 52 and an operating crank 53 spaced thereabove.

The crank is secured to the screw 51 by means of a pin 54, the shank of the screw being first passed through a transverse hole in a short swivel shaft 56. The ends of this swivel shaft are pivotally received in apertured angle plates 57-57 and these members are riveted or welded to the underside of the cross member 41 on opposite sides of the opening 58. This opening in the cross member 41 provides for the passage therethrough of the shank of the adjusting screw and the hub of the crank 53.

A similar swivel shaft 59 is pivotally mounted between a pair of angle plates 61 and these angle plates are affixed to the inner surface of the movable wall 47 of the equalizer bar generally as shown. The swivel shaft is, however, threaded to receive the adjusting screw, and stop or limit nuts 62 and 63 are threadedly received on the adjusting screw above and below the swivel shaft 59. These stop nuts are provided with set screws or lock nuts, not shown, to affix them in position.

It may now be understood that the angular relation of the equalizer bar 43 relative to the lever arms 39 may be altered by rotating the adjusting screw 51 to vary the effective lengths of the lever arms, this effective length being the distance between the centers of the pivot bolts 23 and the ear-like spring attachment members 46 of the equalizer bar.

When the spring tensioning device is adjusted to its lowest possible position, as represented by solid lines, it provides lever arms of the greatest effective length. When so adjusted, the table will lift or carry its maximum load.

The relative positions of the table top, the pivot arms and the equalizer bar, when the top is in

elevated position, are indicated by dashed lines in Figure 3.

Spring enclosures 64-64, formed of sheet metal, extend upwardly from the base to enclose the springs on top and sides.

The locking mechanism 17 permits the top 11 to be secured at any desired elevation and this mechanism preferably includes an arcuate-shaped clamping plate 66, spot welded or otherwise permanently secured, as at 65, to the outer side of the upper end of one of the upper pivot arms 33. The clamping plate 66 is provided with an arcuate shaped slot 67 having as its center the pivot bolt 32. A clamping screw 68, having a clamping knob 69 at its outer end, extends through an opening 71 in the top flange 28, through the arcuate slot 67 in the clamping plate and is engaged at its inner end by the nut 72, which member is secured to and prevented from 20 turning by the nut plate 73. This nut plate is offset, as shown at 74, to permit its being bolted to the inner surface of the upper flange 28.

Tightening the clamping knob 69 will secure the table top at any desired elevation by binding 25 the clamping plate 66 between the nut plate 73 and the top flange 28.

An elevating table such as we have herein described has many novel features and advantages over prior art devices of similar nature. The 30 spring tensioning device 16 depends only partially upon adjustment of the tension of the springs to compensate for or counterbalance loads of various weights which may be placed upon the table top. The mechanism provides for increasing the 35 leverage applied by the lifting springs to the pivot arms to compensate for increased load.

When the spring tensioning device has been properly adjusted to any particular load, the 40 table top, along with its load, may be readily adjusted as to height by loosening the clamping knob 69 and giving the top a slight push either up or down as desired.

A table embodying our inventive idea is dependable, easy and safe to use, relatively inexpensive to manufacture and suited to a wide variety of uses, particularly in offices, for supporting ledgers, posting trays, and card files at the height most convenient for the user.

Although we have described a specific embodiment of our invention, it is apparent that modifications thereof may be made by those skilled in the art. Such modifications may be made without departing from the spirit and scope of our invention as set forth in the appended claims.

55 We claim as our invention:

1. In an elevating table, a base member, a top member disposed thereabove and parallel thereto, at least two parallel arms pivotally connected between the said base and top members, a spring 60 anchored at one of its ends, a lever arm comprising an extension of one of said parallel arms, a tension adjusting member pivotally secured at one end thereof to the free end of the lever arm and at the other end thereof to the free end of the 65 spring, and means for adjusting the angular relation of the tension adjusting member to the lever arm.

2. In an elevating table, a base member, a top member disposed thereabove and parallel thereto, pairs of parallel arms pivotally connected to the base member generally adjacent one end thereof and to the top member generally adjacent the opposite end thereof, the lowermost of said parallel arms having portions thereof extending beyond the points of pivotal connection

with the base and forming lever arms, springs enclosed by the base and anchored at one end thereof, a tension adjusting member pivotally secured at one end thereof to the free ends of the lever arms and at the other end thereof to the free ends of the springs, and means for adjusting the angular relation of the tension adjusting member to the lever arms.

3. In an elevating table, a base, a table top member disposed in spaced, parallel relation to the base, parallel base flanges mounted in upstanding position adjacent one end of the base, parallel table flanges depending from the opposite end of the table and in generally parallel relation with the base flanges, pairs of parallel arms pivotally connected between the base flanges and the table flanges with the points of pivotal connection to each of said flanges offset vertically whereby the pairs of arms may assume positions parallel to the base when the table top member is in lowered position, lever arms comprising extensions of the lowermost arm of each pair of arms, springs each anchored at one end to the base at positions remote from the lever arms, means securing the springs, at their other ends, to the lever arms, and means for varying the tension on the springs.

4. In an elevating table, a base, a table top member disposed in spaced, parallel relation to the base, parallel base flanges mounted in upstanding position adjacent one end of the base, parallel table flanges depending from the opposite end of the table and in generally parallel relation with the base flanges, pairs of parallel arms pivotally connected between the base flanges and the table flanges with the points of pivotal connection to each of said flanges offset vertically whereby the pairs of arms may assume positions parallel to the base when the table top member is in lowered position, lever arms comprising extensions of the lowermost arm of each pair of arms, springs each anchored at one end to the base at positions remote from the lever arms, means securing the springs at their other ends to the lever arms, means for varying the tension on the springs, and locking means operatively connected between one of the parallel arms and an adjacent flange and adapted to prevent relative movement therebetween.

5. In an elevating table, a base, a table top member disposed thereabove and generally par-

allel thereto, parallel base flanges mounted in upstanding position adjacent one end of the base, parallel table flanges depending from the opposite end of the table and in generally parallel relation with the base flanges, pairs of parallel arms pivotally connected between the base flanges and the table flanges with the points of pivotal connection to each of said flanges offset vertically whereby the pairs of arms may assume positions parallel to the base when the table top member is in lowered position, means urging the parallel arms toward a vertical position to thereby elevate the table top member and locking means operatively connected between one of the parallel arms and an adjacent flange for selectively locking said arm and flange members in a plurality of relative positions.

6. In an elevating table, a base, a table top disposed thereabove, pairs of parallel arms pivotally connected therebetween, certain of the arms having extensions beyond the points of pivotal connection with the base, a tension spring anchored at one end thereof to the base at a point remote from the arm extensions, means pivotally connected to the arm extensions at one end thereof and to the free end of the spring at the other end thereof to form a link therebetween, and threaded adjusting means operatively disposed between the said link means and the arm extensions and adapted to vary the angular relation therebetween.
